UNITED STATES PATENT OFFICE

EDWARD J. BRENNAN, OF HASBROUCK HEIGHTS, NEW JERSEY, ASSIGNOR TO FEMININE PRODUCTS, INC., OF NEW YORK, N. Y., A CORPORATION OF NEW YORK

DESIGN FOR A CONTAINER CLOSURE

Application filed March 16, 1933. Serial No. 47,471. Term of patent 14 years.

To all whom it may concern:

Be it known that I, EDWARD J. BRENNAN, a citizen of the United States, residing at 127 Raymond Street, Hasbrouck Heights, Bergen county, State of New Jersey, have invented a new, original, and ornamental Design for a Container Closure, of which the following is a specification, reference being had to the accompanying drawing, forming a part thereof.

Figure 3 is a bottom view of a container closure showing my new design, all of the figures being on an enlarged scale.

I claim:

The ornamental design for a container closure as shown.

EDWARD J. BRENNAN.
